GARMENT HANGER

John M. Oldham, Detroit, Mich., assignor to
Leonard A. Young, Detroit, Mich.

Application July 28, 1934, Serial No. 737,350

27 Claims. (Cl. 223—88)

The main objects of this invention are:

First, to provide a garment hanger which is simple and economical in its parts and inexpensive to manufacture, the arrangement being such that the device readily lends itself to large scale production.

Second, to provide a garment hanger having wire arms provided with means coacting with paper covers thereon to prevent rotation of the latter, whereby they are held in their most effective position for supporting the garment, such as a coat.

Third, to provide a garment hanger consisting of a wire yoke and a paper strut or cross bar of improved construction, the cross bar being adapted to be readily connected with or detached from the yoke so that the yoke may be used with or without the strut.

Objects relating to details and economies of my invention will appear from the description to follow. The invention is defined and pointed out in the claims.

A structure which is a preferred embodiment of my invention is illustrated in the accompanying drawings, in which:

Fig. 1 is a perspective view of a garment hanger embodying the features of my invention with the strut and the yoke covers in assembled relation.

Fig. 2 is an enlarged top plan view of the hanger, a portion of one arm cover being broken away and shown in section on a line corresponding to line 2—2 of Fig. 4.

Fig. 3 is an enlarged fragmentary view partially in front elevation and partially in section showing the corner construction in detail.

Fig. 4 is an enlarged transverse section taken on a line corresponding to line 4—4 of Fig. 2.

Fig. 5 is a transverse section of the strut on line 5—5 of Fig. 3.

Fig. 6 is an enlarged fragmentary view in front elevation of the hook shank and yoke connection, the parts being shown in section at the joint.

Fig. 7 is a front elevational view of the suspension hook and yoke assembly.

Fig. 8 is an enlarged fragmentary view in front elevation of a modification, the inturned finger at the outer end of the yoke arm being straight.

Fig. 9 is a perspective view of another modification.

Fig. 10 is an enlarged transverse section taken on a line corresponding to line 10—10 of Fig. 9.

Fig. 11 is an enlarged perspective view of the strut of the modification.

Fig. 12 is a perspective view of another form of strut.

Fig. 13 is a fragmentary view partially in front elevation and partially in section of a corner construction embodying the use of the strut shown in Fig. 12.

Fig. 14 is a perspective view of another modification of the strut.

Fig. 15 is a fragmentary view partially in section and partially in elevation of a modification of the arm cover.

At the present time, enormous quantities of wire garment hangers of conventional design are being manufactured and sold. With automatic machines making wire garment hangers by the hundreds of thousands, the cost thereof quite closely approaches the cost of the wire. It follows that the reduction in the amount of wire required for each hanger, however slight, will result in a corresponding saving in the cost of manufacture. I aim to make a garment hanger which uses as little wire as possible, but which has sufficient wire to produce the desired results.

Compared to wire, paper is relatively inexpensive, but it lacks sufficient strength except in certain directions, even when suitably formed. Another purpose of my invention is therefore to use paper instead of wire in that portion of the garment hanger where its natural properties and qualities are useful.

In the past, it has been customary for the cleaner to apply paper covers or sleeves on the arms and cross bar of wire garment hangers in certain cases, in order to prevent the metal from coming in contact with the garment. These covers on the arms are formed of relatively light cardboard stock folded over the yoke and/or struts so that the fold constitutes the supporting surface. A feature of my invention is the provision of means on the arms of a hanger yoke for preventing paper covers thereon in the form of relatively stiff flattened tubes from rotating, and so that the covers are held in their most desirable and beneficial position for presenting a supporting surface of substantial width for supporting the garment.

In some cases, in conventional wire garment hangers, the cleaner does not use the cross bar or strut at all, such as where dresses alone or overcoats are to be delivered. In such cases, the cross bar represents a total loss to the cleaner which, although small in each hanger, assumes large proportions where a great number of hangers are considered. Another feature of my invention is, therefore, the provision of a paper strut which is available for use if desired by the clean-

er, but which can be left off and is not necessary when the yoke alone is used. While any kind of detachable strut is suitable for my purpose, I prefer to use one formed of paper which is suitably conformed for the purpose intended and for co-action with my improved wire yoke.

Referring now to drawings, 1 is a suspension hook formed of a single piece of wire and having a straight vertical shank 2. The yoke 3 is also separately formed of one piece of wire, the apex 4 of the yoke being butt welded to the lower end of the shank 2 of the suspension hook. The downwardly and outwardly diverging arms 5, 5 of the yoke are provided with medial lateral offsets 6 and terminate in inturned hooks or fingers 7, the inner ends of which are turned up to provide terminal lugs 8.

By butt welding the suspension hook to the yoke, I save a very substantial amount of stock over the conventional hook form wherein the ends of the wire are twisted at the shank of the suspension hook. Further, the welding operation is performed while the forming operations are taking place on the yoke, the stock being fed to welding position by means of friction feed rolls and screw tightening rolls.

On the arms of the yoke are arranged paper covers 9 in the form of flat stiff tubes held against rotation by the offsets 6 and in place by the shank 2 and end fingers 7. The arm covers are preferably formed of relatively stiff paper stock, such as thin cardboard, in longitudinal strips which are folded and glued together at 10. The offsets in the arms not only serve to support the covers so that they will not twist and a broad surface is presented upwardly, but they also act when the covers are omitted to provide stops with which the shoulder straps of ladies' garments may be engaged to prevent slipping.

The paper strut 11 which I prefer to use is in the form of a flattened tube with its edge portions 12, 12 glued together to form a vertical stiffening flange 13 which extends longitudinally of the strut in depending relation to the tube. Before forming the tube, the inside of the paper strip or cardboard is preferably coated with quick hardening glue or water glass 14 or the like to add stiffness and also to provide the adhesive for securing the edges of the strip together to form the tube.

The ends of the tube are adapted to receive the inturned fingers 7 and their terminal lugs 8 and engage the angles 15 formed by the fingers with the arms 5. This paper strut serves all the purposes of a conventional paper covered wire strut or cross piece of a conventional wire hanger with several advantages as will appear from the description. My structure not only entirely saves the cost of a strut when not used, but it also saves the difference between the cost of a conventional wire strut plus a paper cover therefor and the cost of my improved paper strut.

I contemplate shipping the paper struts in a carton separate from the wire yoke and hook assembly so that the cleaner may apply the struts to the yokes or not as desired or required. Further, the sleeves or arm covers are shipped separately for application by the cleaner to the arms of the yoke when necessary.

While the struts are stiff enough to effectively support the garment, they are preferably made so that repeated use of the hanger is prevented. For sanitary reasons, it is undesirable for cleaners to use garment hangers more than once particularly as they are then passed from one

customer to another. However, the paper strut is very strong and fully effective for the purpose intended when engaged with the arms of the yoke as described above.

If desired, the arms of the yoke may be collapsed toward each other when formed, so that when the strut is inserted it will be necessary to spring the arms outwardly. In this case, the upturned prongs or lugs on the inturned hooks or the arms are not necessary and are omitted, as illustrated by Fig. 8 of the drawings. The upturned prongs or lugs have the advantage of more securely engaging the tubular strut, and also of permitting the use of struts having end holes adapted to receive the upturned prongs, as shown by Figs. 12, 13 and 14 of the drawings.

Referring to Figs. 12 and 13, the strut 16 comprises a flat strip of wood having notches 17, 17, and holes 18 in its ends for receiving the upturned lugs or prongs 8 at the inner ends of 20 the inturned hooks or fingers 7.

In Fig. 14, the strut 19 is of wood of round section having holes 20, 20 spaced from its ends for receiving the upturned prongs 8. Compared to wire, the separately formed struts of wood or 25 paper are relatively inexpensive, and may be entirely omitted from the hanger when not needed. This results in a considerable saving not only to the manufacturer, but also to the cleaner.

Referring to Figs. 9, 10 and 11, the paper strut 30 21 is in the form of a flat tube with the edges secured together to provide a longitudinal depending stiffening flange 22, the ends of the tube receiving the fingers 7, 7 and the terminal lugs 8, 8 coacting with the side walls of the tube 35 to prevent rotation thereof relative to the fingers. While the upper edge of the strut 21 presents less surface to the garment than the tube 11, nevertheless, owing to the coaction of the lugs with the side walls of the tube, a somewhat better 40 construction is provided by the tube 21 than the tube 11. Further, in tube 21 the internal stiffening cement or glue may be omitted, owing to the inherent stiffness of the flat section of tube 21.

Fig. 15 illustrates a modification of the arm cover or sleeve, the sleeve 23 of the modification consisting of a folded strip of cardboard or stiff paper having its edge portions secured together by the connecting tape 24 having glue 25 on 50 the inner surface. In Fig. 15, the parts are shown only partially assembled, the sleeve being shipped in this condition so that it can be readily applied to the arms 5 of the yoke.

From the above description of my invention, it 55 will be apparent to those skilled in the art that I provide an improved garment hanger which is not only simple and economical in its parts, but which is extremely inexpensive to manufacture. Thus, the invention profits both the manufacturer and the cleaner. A very desirable feature of my invention is the detachable strut which may be used or omitted as desired. Another very desirable and equally important feature of the invention is my improved paper strut which is 60 not only considerably less expensive than a wire strut, but which constitutes a non-metallic shield for contact with the garment hung thereon.

I have illustrated and described my improvements in embodiments which I have found very 70 practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters Patent, is:

1. A garment hanger comprising a wire yoke having downwardly diverging arms provided with inturned fingers, the inner ends of which are turned up to provide terminal lugs, paper covers on said arms in the form of flat stiff tubes, and a paper strut in the form of a flattened tube 10 with the edges secured together to provide a depending longitudinal stiffening flange, the ends of the tube receiving the terminal lugs of the inturned fingers and engaging the angles formed by the fingers with the arms.
- 15 2. A garment hanger comprising a yoke having downwardly diverging arms provided with inturned fingers, the inner ends of which are turned up to provide terminal lugs, and a paper strut in the form of a flattened tube, the ends 20 of the tube receiving the terminal lugs of the inturned fingers and engaging the angles formed by the fingers with the arms.
- 25 3. A garment hanger comprising a wire yoke having downwardly diverging arms, provided with medial lateral offsets terminating in inturned fingers, the inner ends of which are turned up to provide terminal lugs, paper covers on said arms in the form of flat stiff tubes held against rotation by said offsets and in place by said shank 30 and fingers, and a paper strut in the form of a flattened tube with the edges secured together to provide a depending longitudinal stiffening flange, the ends of the tube receiving the terminal lugs of the inturned fingers and engaging the angles formed by the fingers with the arms.
- 35 4. A garment hanger comprising a wire yoke having downwardly diverging arms terminating in inturned fingers, the inner ends of which are turned up to provide terminal lugs, and a paper 40 strut in the form of a flattened tube with the edges secured together to provide a depending longitudinal stiffening flange, the ends of the tube receiving the terminal lugs of the inturned fingers and engaging the angles formed by the fingers with the arms.
- 45 5. A garment hanger comprising a wire yoke having downwardly diverging arms provided with inturned fingers, and a paper strut in the form of a flattened tube with the edges secured together to provide a depending longitudinal stiffening flange, the ends of the tube receiving the inturned fingers and engaging the angles formed by the fingers with the arms.
- 50 6. A garment hanger comprising a wire yoke having downwardly diverging arms terminating in inturned fingers, the inner ends of which are turned up to provide terminal lugs, and a strut receiving the terminal lugs of the inturned fingers and engaging the angles formed by the fingers with the arms.
- 55 7. A garment hanger comprising a wire hook having a shank, a wire yoke butt welded at its apex to the lower end of said shank and having downwardly diverging arms, provided with medial lateral offsets, and terminating in inturned fingers, the inner ends of which are turned up to provide terminal lugs, fiber covers on said arms in the form of flat stiff tubes held against rotation by said offsets and in place by said shank 60 and fingers, and a fiber strut receiving the terminal lugs of the inturned fingers and engaging the angles formed by the fingers with the arms.
- 65 8. A garment hanger comprising a wire hook having a shank, a wire yoke butt welded at its apex to the lower end of said shank and having downwardly diverging arms provided with medial lateral offsets, and inturned fingers, the inner ends of which are turned up to provide terminal lugs, fiber covers on said arms in the form of flat stiff tubes held against rotation by said offsets and in place by said shank and fingers, and a fiber strut receiving the terminal lugs of the inturned fingers.
- 70 9. A garment hanger comprising a wire hook having a shank, a wire yoke butt welded at its apex to the lower end of said shank and having downwardly diverging arms terminating in inturned fingers, the inner ends of which are turned up to provide terminal lugs, and a fiber strut receiving the inturned fingers.
- 75 10. A garment hanger comprising a yoke having downwardly diverging arms provided with medial lateral offsets and inturned fingers, and covers on said arms in the form of flat stiff tubes held against rotation by said offsets and in place by said fingers.
- 15 11. A garment hanger comprising a wire hook having a shank, a wire yoke having downwardly diverging arms provided with medial lateral offsets and terminating in inturned fingers, and paper covers on said arms in the form of flat stiff tubes held against rotation by said offsets and in place by said shank and fingers.
- 20 12. A garment hanger comprising a yoke having outwardly and downwardly diverging arms provided with inturned fingers, the ends of which are provided with terminal lugs, and a strut in the form of a flat tube, the ends of the tube receiving said fingers and the terminal lugs coacting with the side walls of the tube to prevent rotation thereof relative to the fingers.
- 25 13. A garment hanger comprising a wire yoke having outwardly and downwardly diverging arms terminating in inturned fingers, the ends of which are turned up to provide terminal lugs, and a paper strut in the form of a flat tube with the edges secured together to provide a longitudinal depending stiffening flange, the ends of the tube receiving said fingers and the terminal lugs coacting with the side walls of the tube to prevent rotation thereof relative to the fingers.
- 30 14. A garment hanger comprising a wire yoke having outwardly and downwardly diverging arms terminating in inturned fingers, the ends of which are turned up to provide terminal lugs, and a paper strut in the form of a flat tube, the ends of the tube receiving said fingers and the terminal lugs coacting with the side walls of the tube to prevent rotation thereof relative to the fingers.
- 35 15. A garment hanger comprising a wire yoke having outwardly and downwardly diverging arms terminating in inturned fingers, the ends of which are turned up to provide terminal lugs, and a fiber strut, the ends of the strut having holes for receiving said terminal lugs and for coacting therewith to prevent rotation of the strut relative to the fingers.
- 40 16. A garment hanger comprising a wire yoke having diverging arms terminating in inturned fingers, a tubular paper strut formed of a strip of material folded upon itself with portions adjacent its edges in lapping relation and having an internal coating of adhesive material constituting a stiffening means, and means for securing the lapping portions together.
- 45 17. A garment hanger comprising a wire yoke having diverging arms terminating in inturned fingers, and a tubular paper strut receiving said fingers and having an internal coating of set adhesive material constituting a stiffening means,

- the tube being formed of a strip folded upon itself with portions adjacent its edges in lapping relation and secured together by the adhesive, such portions providing a longitudinal vertically disposed stiffening flange.
18. A garment hanger comprising a wire yoke having downwardly diverging arms terminating in inturned fingers, and a strut formed of a piece of fibrous material folded longitudinally upon itself to provide a tube, the edge portions of the strip being in lapping relation and adhesively secured together, the adhesive being also applied to the interior surface of the strut and constituting a stiffening means therefor, the ends of the strut receiving the fingers.
19. A garment hanger comprising a wire yoke having downwardly diverging arms provided with inturned fingers, and a strut receiving its fingers and formed of a piece of fibrous material folded longitudinally upon itself to provide a tube, the edge portions of the strip being in lapping relation and secured together.
20. A tubular paper strut for garment hangers formed of a strip of material folded upon itself with portions adjacent its edges in lapping relation and having an internal coating of adhesive material constituting a stiffening means, and means for securing the lapping portions together.
21. A tubular paper strut for garment hangers having an internal coating of set adhesive material constituting a stiffening means, the tube being formed of a strip folded upon itself with portions adjacent its edges in lapping relation and secured together by the adhesive, such portions providing a longitudinal vertically disposed stiffening flange.
22. A garment hanger comprising a wire yoke provided with a hook at its apex and having downwardly diverging arms provided in inturned fingers, the inner ends of which are turned upwardly to provide terminal lugs, and a tubular fiber strut
- receiving the inturned fingers with the upturned lugs in engagement with the top wall of the strut.
23. A garment hanger comprising a wire yoke the arms of which terminate in inturned fingers, the fingers having upwardly projecting lugs, and a tubular fiber strut receiving said inturned fingers, the lugs of which are in internal engagement therewith.
24. A garment hanger comprising a wire yoke having downwardly diverging arms provided with inturned fingers having lateral offsets, and a tubular strut receiving said fingers and of an internal diameter substantially greater than the diameter of the wire, the fingers and their offsets being in supporting engagement with the walls of the strut.
25. A garment hanger comprising a yoke provided with a hook at its apex and having downwardly diverging arms terminating in inturned fingers, the inner ends of which are turned laterally to provide lugs, and a tubular strut receiving the inturned fingers with the lateral lugs in engagement with the wall of the strut.
26. A garment hanger comprising a yoke the arms of which have inturned fingers, the fingers having laterally disposed lugs, and a tubular strut receiving said inturned fingers with the fingers and their lugs in internal engagement therewith and acting to prevent relative movement of the strut.
27. A garment hanger comprising a wire yoke having downwardly diverging arms provided with inturned fingers having lateral offsets, and a tubular strut of an internal diameter substantially greater than the diameter of the fingers, receiving said fingers and their lugs, the fingers and their lugs being in internal supporting engagement with the walls of the strut and acting to prevent rotative movement thereof.

JOHN M. OLDHAM. 40
